UNITED STATES PATENT OFFICE.

STEFAN WILOCH, OF SCHENECTADY, NEW YORK.

PADLOCK.

1,424,543.

Specification of Letters Patent. Patented Aug. 1, 1922.

Application filed February 2, 1922. Serial No. 533,637.

To all whom it may concern:

Be it known that I, STEFAN WILOCH, a citizen of the United States of America, residing at Schenectady, in the county of 5 Schenectady and State of New York, have invented certain new and useful Improvements in Padlocks, of which the following is a specification.

This invention relates to certain new and 10 useful improvements in padlocks, and has particular reference to a padlock embodying a barrel portion and a shackle bolt detachably connected to the barrel portion, with a special type of key for releasing the 15 shackle bolt.

The primary object of the invention resides in the provision of a padlock having an internally threaded barrel portion with a screw plug threaded therein and operable 20 by a special type of key for shifting the plug to engaging and disengaging positions with respect to a shackle bolt.

A further object of the invention embodies in a padlock of the type above set forth, 25 a peculiar engagement between the key and screw plug which only renders the lock operable by the employment of a particular key.

A still further object of the invention is 30 to provide a padlock of the above type, wherein a shackle bolt is to be entirely disengaged from a barrel member and with the employment of a special type of key to affect such disengagement, the key opening 35 in the barrel being of a configuration, only to permit the entrance of the key into the barrel by a portion of the key engaging a movable member carried by the shackle bolt with a subsequent engagement between the 40 key and the screw plug contained in the barrel for retaining the shackle bolt locked to the barrel.

With the above and other objects in view which will appear as the description proceeds, my invention resides in the novel construction, combination, adaptation and arrangement of parts hereinafter described and claimed.

In the drawings forming a part of this application, and in which like reference characters designate corresponding parts throughout the several views,

Figure 1 is a longitudinal sectional view of a padlock constructed in accordance with 55 the present invention, showing the internally threaded barrel, the screw plug therein

engaging the shackle bolt and the spring pressed movable member of the shackle bolt engaging the key to prevent entrance of the key into the barrel of the lock, 60

Figure 2 is an end elevational view of the lock showing the key receiving opening in the end of the lock barrel,

Figure 3 is a side elevational view of the lock, partly broken away and shown in section with the operating key moved to an engaging position with a movable member carried by the shackle bolt to permit the entry of the key into the barrel of the lock, 65

Figure 4 is a side elevational view, partly 70 broken away and shown in section, with the key engaging the screw plug in the barrel of the lock with the screw plug shifted to a disengaging position relative to the shackle bolt,

Figure 5 is a side elevational view of the shackle bolt disengaged from the barrel of the lock showing the spring pressed plunger carried thereby for cooperation with the key, 75

Figure 6 is an end elevational view of the shackle bolt showing the opening in one arm thereof for receiving the pin carried by the screw plug and the tensioned plunger for cooperation with the key, and 80

Figure 7 is an end elevational view of the key employed for operating the lock.

Referring more in detail to the accompanying drawing, it being understood that the preferred form of the invention is herein 90 illustrated, there is shown a padlock embodying a barrel portion 1 having an open end closed by a plug 2 suitably anchored therein, as by welding or otherwise, the opposite end wall 3 being cast integral with the barrel 1 95 and having a key receiving opening 4 of the type best illustrated in Figure 2. The inner wall of the barrel 1 is provided with screw threads 5 of comparatively deep pitch and extending substantially from end to 100 end thereof.

A screw plug 6 of the type best illustrated in Figure 1, is threaded for engagement with the threads 5 of the barrel 1 the outer end of the plug 6 being of substantially 105 conical form as illustrated at 7, and carrying a pin 8 for engagement with a shackle bolt, later to be described, with the free end of the pin 8 received in the socket 9 formed in the inner face of the closure plug 110 2 of the barrel. The inner end of the screw plug 6 carries an axial projection or ex-

tension having a polygonal base portion 10, with a cylindrical stud 11 projecting from the polygonal base while a lateral pin 12 is carried by the stud 11 intermediate the ends 5 thereof.

The shackle bolt associated with the barrel of the lock is of U-formation, embodying relatively long and short side legs 13 and 14 respectively, connected by an arm 15, openings 16 being provided in the side wall of the barrel 1 for the reception of the free ends of the side legs of the shackle bolt. As shown in Figures 1 and 4, the leg 13 of the shackle bolt that enters the barrel 1, is 15 provided with a transverse opening 17 for the reception of the pin 8 carried by the screw plug 6, the engagement thereof being shown in Figure 1 with the shackle bolt locked to the barrel.

20 The legs 14 of the shackle bolt and the screw plug operating key 18 are constructed for cooperation to permit entry of the key 18 into the opening 4 of the end wall of the barrel, the inner end of the leg 14 being 25 provided with a socket for the reception of a plunger 19 spring pressed as at 20 normally to be pressed outwardly of the shackle bolt leg with the projecting end of the plunger 19 carrying a finger extension 21. The construction of the key 18 is more clearly shown 30 in Figure 4 of the drawing, the shank thereof carrying a finger gripping head 22, while the opposite end of the key shank is provided with an axial socket 23 with the outer end 35 of the socket being of polygonal formation. The shank of the key, adjacent the socket 24 is provided with a longitudinally extending internal slot 25 communicating with the socket 23, while the end of the key shank 40 adjacent the slot carries an extension 26, with an outwardly directed lug 27 upon the outer end thereof.

45 From the above detailed description of the device, it is believed that the construction and operation thereof will at once be apparent, it being noted that the key opening 4 in the end wall 3 of the lock barrel is provided with a side slot 4^a to provide a clearance for the key extension 26 and lug 50 27 when the key 18 is inserted into the key opening as shown in Figure 1. When the key is so inserted, it will be noted from an inspection of Figure 1 of the drawing that the inner end of the key shank engages the 55 plunger finger 21, preventing further entrance of the key into the lock barrel. The key opening 4, and the shank of the key, are of such dimensions as to permit free rotation of the key in said opening, and upon 60 rotation thereof the lug 27 upon the key extension 26 will be moved into engagement with the lower end of the spring pressed plunger 19, at a point intermediately of the finger extension 21, it being noted that the 65 lower ends of the plunger and finger are

curved to provide a riding surface for the key extension and lug with the plunger 19 subsequently moved into the leg 14 of the shackle bolt to displace the plunger 19 from the sliding path of movement of the key 70 18 during the correct positioning thereof in the lock barrel. With the parts so disposed, the key 18 is further inserted into the lock barrel 1 with the stud 11 carried by the screw bolt 6 received in the socket 23 formed 75 in the inner end of the key, the polygonal base portion 10 of the screw plug extension being received in the polygonal socket of the outer end of the key socket 23, and with the pin upon the stud 11 received in the 80 side slot 25 of the key. Upon rotating the key 18 in the proper direction, the screw bolt 6 is axially shifted by its threaded connection with the lock barrel 1 to remove the pin 8 carried by the screw bolt from engagement with the opening 17 in the leg 13 of the shackle bolt, the parts being shifted to the position shown in Figure 4 at which time the shackle bolt is freely removable 85 from the barrel as will be readily understood. To remove the key from the lock, the same is shifted to a disengaging position with respect to the screw bolt 6 and upon rotation thereof the extension 26 and the lug 27 is disposed for registration with the 90 side slot 4^a of the key opening 4 whereupon the key is removed from the lock casing.

95 As above stated, the preferred embodiment of the invention is herein illustrated, but it is to be understood that various 100 changes are contemplated such as modifying the construction of the extension carried by the screw bolt 6 and embodying the base polygonal portion 10, the stud 11 and the side pin or lug 12, the operating end of the 105 key also being capable of various forms for cooperation with the screw bolt extension.

110 What is claimed is:—

1. In a padlock of the type described, a barrel portion, a shackle bolt associated therewith, said shackle bolt having side legs entering the lock barrel, and key operated means within the barrel adapted to be moved into engagement with one of the legs for anchoring the shackle bolt to the barrel, and 115 cooperating means carried by the other leg of the shackle bolt and the operating key adapted for cooperation prior to engagement of the key with the operating means for releasing the other leg of the shackle bolt. 120

2. In a padlock of the type described, a barrel, said barrel being internally threaded and having a key opening formed in one end thereof, a screw bolt threaded into the barrel, a shackle bolt having side legs received 125 in a side wall of the barrel with a transverse opening formed in one of said legs, a pin carried by the screw bolt adapted to be received in the opening in the shackle bolt leg, and a key for axially shifting the screw bolt 130

to move the pin carried thereby into and out of engagement with the shackle bolt leg.

3. In a padlock of the type described, a barrel, said barrel being internally threaded and having a key opening formed in one end thereof, a screw bolt threaded into the barrel, a shackle bolt having side legs received in a side wall of the barrel with a transverse opening formed in one of said legs, a pin 10 carried by the screw bolt adapted to be received within the opening in the shackle bolt legs, and a key for actually shifting the screw bolt to move the pin carried thereby into and out of engagement with the shackle 15 bolt leg, a tensioned plunger projecting from the inner end of the other shackle bolt leg and traversing the key opening in the end wall of the barrel, and means carried by said key adapted to be moved into engagement with the plunger for shifting the same in the key 40 opening to permit entrance of the key into the barrel, a projection carried by the inner end of the screw bolt embodying a polygonal base portion and a cylindrical stud, and an axial socket in the inner end of the key having a polygonal portion at the outer end thereof for cooperation with the screw bolt extension to effect rotation of the screw bolt upon rotation of the key.
4. In a padlock of the type described, a barrel, said barrel being internally threaded and having a key opening formed in one end thereof, a screw bolt threaded into the barrel, a shackle bolt having side legs received in a side wall of the barrel with a transverse opening formed in one of said legs, a pin 20 carried by the screw bolt adapted to be received within the opening in the shackle 25 bolt legs, and a key for actually shifting the screw bolt to move the pin carried thereby laterally of the key opening to permit entrance of the key into the barrel.
5. In a padlock of the type described, a barrel having a key opening in one end thereof, a shackle bolt detachably connected to said barrel, key operated means within the barrel for retaining the shackle bolt in locked position with respect thereto, a key 30 for operating said shackle bolt retaining means, and cooperating means carried by the key and shackle bolt adapted for operation prior to engagement between the key and the shackle bolt retaining means.

In testimony whereof I affix my signature.

STEFAN WILOCH.
